CONVEYER

Ronald E. J. Nordquist, Maplewood, N. J., assignor to American Can Company, New York, N. Y., a corporation of New Jersey

Application December 10, 1941, Serial No. 422,434

5 Claims. (Cl. 198—103)

The present invention relates to conveyers and has particular reference to maintaining endless chain conveyers in timed relation with other co-operating feed members irrespective of the amount of slack which may be created in the chains.

Endless chain conveyers are frequently used in various industries for carrying articles from one place to another in time with other moving parts of machinery. An example of such an adaptation is in the container or can making industry where conveyers and turrets, star wheels, and valves having pockets are often used in timed relation to convey cans through one or more machines. Where such combinations of conveyers and rotating members are used in heat treating machines, considerable difficulty is often experienced in expansion of the conveyer chain with a corresponding throwing out of time of the chain with the rotating members.

The instant invention contemplates overcoming this difficulty by providing a yieldable mounting for the conveyer chain so that any slack created by an expansion of the chain will be readily taken up without throwing the chain out of time with cooperating feed members.

An object therefore of the invention is the provision of an endless chain conveyer operating in cooperation with other feed members wherein the conveyer is carried on a flexible mounting which permits of taking up any slack created in the chain, while maintaining the operation of the chain in time with the other feed members.

Another object is the provision of a mounting for such a conveyer chain wherein slack, created in the chain, may be taken up in two or more sections and in different amounts so that the chain in passing certain places adjacent the cooperating feed members will be maintained in timed relation with those members irrespective of the amount of slack in the chain.

Numerous other objects and advantages of the invention will be apparent as it is better understood from the following description, which, taken in connection with the accompanying drawings, discloses a preferred embodiment thereof.

Referring to the drawings:

Figure 1 is a vertical sectional view through a conveyer mechanism embodying the instant invention, with parts broken away;

Fig. 2 is a vertical section taken substantially along the broken line 2—2 in Fig. 1, with parts broken away;

Fig. 3 is a vertical sectional view through the

gear drive casing as viewed from the upper right of Fig. 2; and

Fig. 4 is a horizontal section taken substantially along the broken line 4—4 in Fig. 1.

As a preferred embodiment of the instant invention the drawings illustrate principal parts of the can sterilizing portion of a machine in which sheet metal cans are sterilized, filled with a product, and are sealed prior to shipment and storage. In such a machine empty cans A (Fig. 1) in a horizontal position are introduced into a sterilizing chamber 11 by way of a rotating inlet valve or delivery transfer member 12.

Within the chamber 11 the cans are transferred to a pair of endless chain conveyers 13 which are located side by side and which have spaced prongs or flights 14 for propelling the cans through the chamber. While in the chamber the cans are subjected to a sterilizing treatment such as steam or other suitable medium which is circulated through the chamber. After being sterilized the cans are transferred to a rotary outlet valve or discharge transfer member 15 which discharges the cans from the chamber.

The sterilizing chamber 11 is enclosed by walls of a pair of superimposed connecting casings 21, 22 which are bolted together and which constitute part of the main frame of the machine. Adjacent the can entrance end of the casing 21, a cylindrical valve seat 23 is bolted in place and is formed with an inlet opening 24 through which the cans A are introduced into the chamber. This opening is sealed by the valve 12 which is mounted on a shaft 26 journaled in bearings formed in the upper casing 21. The valve is formed with a plurality of pockets 27 which are spaced around its periphery for carrying the cans into the chamber in timed order.

The can discharge valve 15 is located adjacent the can outlet end of the casing 21 and is disposed in a cylindrical valve seat 31 bolted to the casing. The valve seat is formed with a can outlet opening 32 through which the sterilized cans A are passed from the chamber to the valve. The cans are received in timed order in pockets 33 which are spaced around the periphery of the valve.

The discharge valve 15 is mounted on a shaft 34 which is journaled in bearings formed in the upper casing 21. Cans received in the valve pockets 33 are carried through the valve seat to a discharge opening 36 where they are discharged to any suitable place of deposit by way of a runway 37 or other suitable device.

The endless chain conveyers 13 located within

the sterilizing chamber 11 convey the empty cans along a U-shaped path of travel which extends from the can inlet opening 24 in the valve seat 23, down through the casings 21, 22, and then up toward the outlet opening 32 in the discharge valve seat 31. During this travel, the cans are confined between the conveyer flights 14 of the chain by a pair of inner and outer guide rails 41, 42 which are disposed adjacent the chains.

The conveyer chains 13 operate over a plurality of sprockets located within the chamber 11. Beginning at the inlet valve 12, the chains take over a pair of spaced inlet drive sprockets 43 which are disposed adjacent the can inlet opening 24 in the valve seat. The chains then extend down into the chamber in parallelism with the guide rails 41, 42 and adjacent the bend in the rails near the bottom of the chamber, they take over a pair of spaced lower tightener sprockets 45.

After leaving the lower tightener sprockets 45 the chains 13 extend up along the guide rails 41, 42. Adjacent the can outlet opening 32 in the discharge valve 15, they take over a pair of spaced discharge drive sprockets 47. At the discharge drive sprockets the chains extend down in a loop where they pass under a pair of spaced upper tightener sprockets 49 and then extend up over the inlet drive sprockets 43 mentioned above. This completes the circuit of the chains.

The inlet drive sprockets 43 and discharge drive sprockets 47 are mounted on respective drive shafts 51, 52 journaled in bearings 53 (Fig. 2) formed in the upper casing 21. These drive shafts and the valve shafts 26, 34 are rotated in unison and in timed relation so that the can flights 14 on the chains 13 passing over the sprockets will be maintained in timed relation with the pockets 27, 33 of the respective valves 12, 15. Hence the cans upon entering the chamber and upon leaving the chamber will be properly received and discharged by the conveyer chains.

This timing of the drive sprockets 43, 47 and valves 12, 15 is brought about by a gear train best illustrated in Figs. 2 and 3. The train is operated by a bevel driving gear 56 which is mounted on a main drive shaft 57 journaled in a bearing 58 formed in the upper casing 21. This drive shaft may be rotated in any suitable manner.

The driving gear 56 meshes with and drives a bevel gear 61 mounted on a horizontal shaft 62 journaled in suitable bearings in the upper casing 21. This shaft also carries a spur gear 63 which meshes with a gear 64 mounted on the inlet driving sprocket shaft 51. The sprocket gear 64 meshes with and drives a gear 65 mounted on the inlet valve shaft 26 and thus rotates this valve in time with its associated sprockets 43.

The sprocket gear 64 meshes with an idler gear 66 mounted on a shaft 67 journaled in suitable bearings formed in the upper casing 21. The idler gear meshes with a gear 68 mounted on the discharge sprocket drive shaft 52 and this gear meshes with a gear 69 mounted on the discharge valve shaft 34. In this manner the discharge valve 15 is rotated in time with its cooperating sprockets 47. Thus positive timing is always maintained between the valve pockets and the flights 14 on the conveyer chains 13 as they pass over the driving sprockets.

Any slack which is created in the chains 13 due to expansion caused by the sterilizing heat maintained in the chamber 11, is compensated

for by the tightener sprockets 45, 49. For this purpose the lower tightener sprockets 45 are mounted on a stationary shaft 72 (Figs. 1, 2 and 4) the ends of which are seated in and bolted to half bearings 73 formed in a pair of swing arms 74. The arms are mounted on a pivot shaft 75 carried in a pair of spaced bearing lugs 76 which extend out from the lower casing 22.

The sprocket shaft 72 and the sprockets 45 thereon are pressed downwardly against the chains 13 by a yoke 81 which straddles the two sprockets. The yoke is provided with half bearings 82 which bear down on the sprocket shaft 72 adjacent the swing arms 74. The yoke carries a vertical rod 83 which extends up through a bearing 84 formed in a bracket 85 bolted to the lower casing 22.

A compression spring 86 disposed around the rod 83 and interposed between the bearing 84 and the yoke 81 supplies the pressure on the tightener sprockets 45 to keep taut those portions of the chains that move along the can guide rails 41, 42. Locknuts 87 threaded on the upper end of the yoke rod are provided to limit the travel of the sprockets in case such a limitation be found necessary. It is this tightener device that takes up any slack in the chains in the lower portion of the chamber and thus maintains them taut without in any way interfering with the timing of the chains as they pass over the drive sprockets 43, 47.

In a similar manner, portions of the chains 13 which extend down between the drive sprockets 43, 47 in the upper portion of the chamber 11, are maintained in a taut condition without interfering with the timing of the chains as they pass over the drive sprockets. In this upper end of the chamber the tightener sprockets 49 are mounted on a shaft 91 (Fig. 1).

The ends of the shaft 91 engage under half bearings 92 formed in a pair of spaced swing arms 93. The arms are mounted on a pivot shaft 94 carried in bearing lugs 95 formed on a web section 96 of the upper casing 21. The outer ends of the arms are connected by a bridge section 97 (see also Fig. 2) to which one end of a tension spring 98 is connected. The opposite end of the spring is connected to a lug 99 formed on the bracket 85. It is this spring that pulls down on the swing arms 93 and thus applies a pressure on the upper tightener sprocket shaft 91 and sprockets 49 mounted thereon to maintain the upper portion of the chains taut independently of the lower portion of the chains.

In this manner all portions of the chains on each side of the driving sprockets are kept taut irrespective of each other without in any way affecting the timing of the chains as they pass over the driving sprockets. The chains and their flights 14 are always in time with the valve pockets 27, 33 at the locality where the pockets and the chain flights are brought into registry to transfer the cans from one to the other.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a conveyer mechanism, the combination

of a pair of spaced rotary chamber sealing valves each having peripheral pockets thereon for delivering containers to and discharging the containers from a single intermediately disposed endless conveyer having spaced flights thereon successively movable to adjacent the pockets of said valves for carrying containers received from said delivery valve, said valves each having an independent conveyer sprocket member disposed adjacent thereto for movably supporting said conveyer between said valves, a single power shaft for directly driving said conveyer sprocket members and said valves in timed relation to maintain said conveyer flights in successive registry with the peripheral valve pockets, and a spring tension controlled tightener device connected to spaced portions of said conveyer for continuously maintaining the latter taut without disturbing the timed relation of said conveyer with the rotary movement of said delivery and discharge valves.

2. In a conveyer mechanism, the combination of a pair of spaced rotary chamber sealing valves each having peripheral pockets thereon for delivering containers to and discharging the containers from a single intermediately disposed endless conveyer having spaced flights thereon successively movable to adjacent the pockets of said valves for carrying containers received from said delivery valve, said valves each having an independent conveyer sprocket member rotatably mounted adjacent thereto for movably supporting said conveyer between said valves, a single power shaft for directly driving said conveyer sprocket members and said valves in timed relation to maintain said conveyer flights in successive registry with the peripheral valve pockets, a pair of tightener sprockets rotatably engaging spaced portions of said conveyer, means for mounting said sprockets for bodily floating movement, and a spring tension controlled tightener device connected to each of said sprocket mounting means for continuously maintaining the conveyer taut by taking up slack at spaced portions thereof without disturbing the timed relation of said conveyer with the rotary movement of said delivery and discharge valves.

3. In a conveyer mechanism, the combination of a pair of spaced rotary chamber sealing valves each having peripheral pockets thereon for delivering containers to and discharging the containers from a single intermediately disposed endless conveyer having spaced flights thereon successively movable to adjacent the pockets of said valves for carrying containers received from said delivery valve, said valves each having an independent conveyer sprocket member rotatably mounted adjacent thereto for movably supporting said conveyer between said valves, a single power shaft for directly driving said conveyer

60

sprocket members and said valves in timed relation to maintain said conveyer flights in successive registry with the peripheral valve pockets, a pair of tightener sprockets rotatably engaging opposite portions of said endless conveyer, a pair of pivotally mounted arms in which said sprockets are respectively journaled for bodily floating movement, and spring elements respectively connected to the outer ends of said arms for continuously maintaining said sprockets in taut engagement with said conveyer at opposite portions thereof, whereby to distribute the taking up of conveyer slack to insure against disturbing the timed relation of said conveyer with the rotary movement of said delivery and discharge valves.

4. In a conveyer mechanism including a pair of spaced rotary transfer members each having peripheral pockets thereon for delivering containers to and discharging the containers from a single intermediately disposed endless conveyer having spaced flights thereon successively movable to adjacent the pockets of said transfer members for carrying containers received from said delivery transfer member toward said discharge transfer member, the combination of means for movably supporting said conveyer between said transfer members, means for driving said conveyer, a pair of tightener sprockets rotatably engaging spaced portions of said conveyer, means for mounting said sprockets for bodily floating movement, and a spring tension controlled tightener device connected to each of said sprocket mounting means for continuously maintaining the conveyer taut by taking up slack at spaced portions thereof.

5. In a conveyer mechanism including a pair of spaced rotary transfer members each having peripheral pockets thereon for delivering containers to and discharging the containers from a single intermediately disposed endless conveyer having spaced flights thereon successively movable to adjacent the pockets of said transfer members for carrying containers received from said delivery transfer member toward said discharge transfer member, the combination of means for movably supporting said conveyer between said transfer members, means for driving said conveyer, a pair of tightener sprockets rotatably engaging opposite portions of said endless conveyer, a pair of pivotally mounted arms in which said sprockets are respectively journaled for bodily floating movement, and spring elements respectively connected to the outer ends of said arms for continuously maintaining said sprockets in taut engagement with said conveyer at opposite portions thereof, whereby to distribute the taking up of conveyer slack to spaced portions thereof.

RONALD E. J. NORDQUIST.
